UNITED STATES PATENT OFFICE.

JOHN PAXTON, OF WASHINGTON, DISTRICT OF COLUMBIA.

DESIGN FOR A SCARF-PIN.

SPECIFICATION forming part of Design No. 11,672, dated March 9, 1880.

Application filed December 13, 1879. Term of patent 3½ years.

To all whom it may concern:

Be it known that I, JOHN PAXTON, of Washington, District of Columbia, have invented a new and original Design for Articles of Jewelry, of which the following is a specification.

My design consists of the representation of the figure 4, combined with the representation of a pin and of the letter A, the whole being united substantially as shown in and by the accompanying drawing.

Pins, studs, and other articles of jewelry may be ornamented by the above characters and figures.

I claim—

The design for a scarf-pin or other like article, consisting of the representation of the figure 4 and of a pin and of the letter A, grouped together substantially as set forth.

In testimony whereof I have signed my name to this specification in the presence of two subscribing witnesses.

JOHN PAXTON.
